UNITED STATES PATENT OFFICE.

JOHANNES ROTH, OF LUDWIGSHAFEN-ON-THE-RHINE, GERMANY.

AUTOMATIC TILE-MACHINE.

1,015,588.

Specification of Letters Patent.

Patented Jan. 23, 1912.

Application filed November 7, 1910. Serial No. 591,002.

To all whom it may concern:

Be it known that I, JOHANNES ROTH, factory owner, German subject, residing at No. 202 Frankenthalerstrasse, Ludwigshafen-on-the-Rhine, Germany, have invented new and useful Improvements in Automatic Tile-Machines, of which the following is a specification.

This invention relates to automatic tile cutters of the kind in which the moving stream of clay actuates the cutting devices, which to such end are geared to a controlling shaft rotated by a transmission gear that is connected to guide rollers for the stream of clay caused by the latter to revolve.

The invention consists in certain features of novelty which will appear from the following description and be particularly pointed out in the appended claims.

One illustrative embodiment of my invention is represented by way of example in the accompanying drawings wherein:

Figure 1 is a longitudinal section through the carriage and through a part of the main frame of the machine, Fig. 2 a vertical section taken on the line A—B in Fig. 1 as seen in the direction of the issuing stream of clay, and Fig. 3 a vertical section taken on the line C—D in Fig. 1, also as seen in the direction of the forward movement of the stream of clay, while Fig. 4 is a side elevation showing part of the locking mechanism for the lug-cutter, and Fig. 5 is a diagrammatic side elevation of the belt gearing driving the control spindle, Fig. 6 a plan of the machine, Fig. 7 an enlarged detail view more fully described hereafter, Fig. 8 a perspective detail view of a cam referred to later on.

Referring to the drawing, the stream of clay 1, issuing in the direction of the arrow shown in Fig. 1 from the die or mold, first arrives in a well-known manner on the driving rolls 3, which are thereby set in rotation, and then on the smaller guide rolls 60, of which some are journaled in the stationary frame 1' of the machine and others in the well-known carriage 61 running on rails 62. The carriage 61 carries the requisite cutting, punching and marking devices, hereinafter described, driven in common by

the driving shaft 11, which in a well-known manner is connected by a friction clutch 12 to a counter shaft (not shown).

As shown in Figs. 2 and 5, the belt pulleys 4, driving a control spindle 2 by means of the belt pulley 5 on one end thereof and a belt 4^a or the like, are fast on the outside projecting ends of the shafts 3' of the two driving rollers 3. The other end of the control spindle 2 has secured on it a cam 6 (Figs. 7 and 8) whose beveled face 6^a coacts once during each revolution of the control spindle with a lever 7 in such a manner that this lever is rocked inwardly against the action of a spring 8 around its pivot 7^a, journaled in a bracket on the machine frame 1', and its upper end lifted from an abutment 7^b adjustable on this frame. While the machine is working the bottom end of the lever 7 rests alternately against one of two rectilinear, radial faces 9 of a cam 10 keyed on the shaft 11. For the purpose of driving the cutting devices the shaft 11 also has secured fast on it a crank 13 whose pin, carrying an antifriction roller 14, is movable in a slot 15 in the two-armed lever 16. The latter is fulcrumed on the pivot 16^a in a bracket 16^b attached to the frame 1' and carries at its top end a pin 17, provided with an antifriction roller 18, movable in a slot 19 in the slide-frame 20 which is guided in the upright frame 21 of the carriage 61 and arranged to operate the cutting devices, as will be described hereafter. To such end, as shown in Figs. 2 and 6, the top and the bottom sliding rod of the frame 20 are each formed as a toothed rack 63, in which a spur wheel 64, fast on a pivot 65 journaled in the frame 21, meshes. With each pivot 65 a sleeve 66 is connected that carries two arms 67, while on each arm 67 a sleeve 68 is adapted to slide. The sleeves 68 carry the pattern-cutting wire 69 stretched between them, as will be seen from Fig. 2. The two upper and the two lower sleeves 68 are respectively connected together by a pin carrying a roller 70 engaging in the upper or the lower, respectively, of the guides 72 which in a well-known manner are interchangeably connected with the frame 21. According in each instance as the guides 72 have the shape of a pointed arch, are circu-

lar, segmental, hexagonal or rhomboidal, an exactly similarly shaped front face of the tile will be obtained.

For the purpose of imparting the movement of the frame 20 to the cutter which is to produce the straight back face of the tiles and for actuating by means of the same frame also certain punching and marking devices, more fully referred to hereafter, the 10 top rod of the frame is provided with a slotted guide 26 engaged by an antifriction roller 25 of an arm 24 fast on a shaft 23 which extends longitudinally of the machine and is journaled in two brackets 22. One of 15 the latter is attached to the frame 21 of the carriage 61 and the other to a like frame 21^a thereof.

As shown in Figs. 1 and 3, the straight cutter consists of a bow 37, fixed on the shaft 23, and the cutting wire 38, stretched between the ends of such bow. The bow 37 is adjustable along the shaft 23, in order that different lengths of tile can be cut. The shaft 23 carries fast on it a lever 27, provided with an antifriction roller 28, that engages in the slot 29 of a guide piece 30 (Figs. 1 and 3). This slot is shaped so that the motion of the lever 27 causes the guide piece to reciprocate in vertical direction. 20 The guide piece 30 has a vertical forked arm 31 which clasps the boss of the lever 27. The bottom ends of the guide piece 30 are rigid with a bow or stirrup 32 which is pivotally attached to the free ends of arms 33 25 fast on a transverse shaft 34, mounted in the frame 21^a of the carriage 61 and which carries two punches 35 for making the nail holes and the stamp 36 for impressing the mark of the firm. The stamp 36 is preferably guided by a centrally-arranged pin 36' 30 slidable in an eye 36'' of the frame 21^a of the carriage 61.

The well-known lug-cutter 48, the cutting wire of which is designated by 50, is operated by the following means. The shaft 34 is fitted with a clutch-coupling, of which one member, 39, is fast thereon, whereas the other, 40, is loose on it and prevented from being displaced longitudinally axially, the 45 member 40 has an arm 41, whose free end is pivotally connected by a rod 42 with an arm 43 of a countershaft 44 likewise mounted in the frame 21^a. This shaft has fast on it two levers 45, to whose free ends 50 a bow or stirrup 46 having a pin 47 guided in a sleeve 51 attached to the carriage 61 is pivotally connected. On this pin the lug-cutter 48 is mounted which comprises an antifriction roller 49 and the cutting wire 55 50 and is secured in its elevated or operative position by an elastic catch 53 engaging an arm 52 of the shaft 44 in the manner represented in Fig. 4. The catch 53 is at 53'' attached to a bracket 53''' depending from the frame 21^a. The arm 52 is locked

in this manner until on the motion of the carriage 61 a projection 53' of the catch 53 strikes against an adjustable stop 54 on the main frame, the catch thus becoming bent back so that it releases the arm 52, 70 whereupon the lug-cutter can return under the influence of its own weight into its normal position. The lug-cutter is able to fall back in this manner owing, on the one hand, to the clutch member 40 being mounted only 75 loosely on the shaft 34, and, on the other hand, to the clutch member 39 being returned alone into its normal position, when the cutters 69 and 38 are returned into their normal positions, so that a gap permitting 80 the parts designated by the numerals 40 to 52 inclusive to fall back at the proper moment is formed between the clutch members. Consequently, the adjustment and position of the stop 54 on the main frame 85 determine not only the time when the lug-cutter descends, but also the length of the lug left on the stream of clay.

As mentioned above, the driven pulley 5 of the control spindle has to be selected corresponding to the length of tile; the smaller 90 its periphery is, the more rapidly will the cutting operations follow one another. But in order that the shaft 2 may always be certainly driven when the belt pulley 5 is 95 changed, I provide, in addition, an adjustable idler 55 for the belt 4^a (Fig. 5).

The carriage 61 derives its motion from the spindle 2 by the following arrangement. The carriage 61 has an arm 61^a to which a 100 rod 78, pivotally connected by means of links 76 to the stationary frame 77, and a rod 81 are jointedly attached. The rod 78 is under the action of a pin 74 projecting from a disk 73 mounted on the spindle 2. 105 This pin serves to move the carriage in the direction of the arrow shown in Fig. 1. The rod 81 is pivotally connected with a lever 80 that is carried by the frame 77 and provided with a roller 79 adapted to be acted 110 upon by a cam 75 rigid with the disk 73. This cam is designed to move the carriage in opposite direction to the said arrow.

From the foregoing description it will be understood that the action of the tile cutter 115 briefly is as follows: The moving stream of clay rotates the rolls 3 and thus also by means of the pulleys 4 and 5 the spindle 2. On each revolution of the latter the lever 7 is by the cam 6 moved against the action of 120 the spring 8 so as to release the cam 10 mounted on the driving shaft 11. This is now rotated by the friction coupling 12 until after a half-revolution the second surface 9 is engaged by the lever 7. On the 125 rotation of the shaft 11 the lever 16 is moved on its pin 16^a so as to displace the frame 20 transversely. The motion of this frame causes the sleeves 66 together with the arms 67 to turn on the pins 65 so that the rollers 130

70 slide in their guides 72, the sleeves 68 moving along the arms 67 in accordance with the shape of the guides 72. In this way the pattern-cutting wire 69 is caused 5 to act, the form of cut produced depending upon the shape of the interchangeable guides 72. By the gearing 24, 25, 26 the shaft 23 is rotated on the displacement of the frame 20, and by means of the gearing 27, 28, 30, 10 33 the rotation of the shaft 23 causes the shaft 34 to turn so that by the gearing 39 to 45 the lug cutter 48 is raised into its operative position. On this operation the rotation of the shaft 44 brings about the 15 engagement of the arm 52 with the catch 53 so as to lock the lug cutter in its operative position. The lug cutter is maintained in such position until on the motion of the carriage 61 the projection 53' of the catch 20 53 strikes against the stop 54, provided on the stationary frame 1', so as to release the lug cutter, which then falls back into its position of rest after its wire 50 has in a well-known manner cut away to some length 25 the rib on the under side of the stream of clay. For regulating the amount of the forward movement of the carriage the pressure pin 74 is arranged adjustable in a slot 82 provided with a suitable scale 83.

30 I claim:—

1. In an automatic tile-machine, the combination, with the main frame and a main shaft journaled therein, of driving rolls journaled in said frame, a control spindle 35 journaled in said frame geared with said driving rolls, a carriage, carrying guide rolls, movable on said frame, means driven by the control spindle for reciprocating the carriage, the said rolls being designated to 40 carry and be moved by the stream of clay; a figure or curve cutter, a rectilinear cutter, a punching device and a meshing device mounted on said carriage for cutting, punching and marking the stream of clay, 45 a reciprocating cutter-frame mounted on the carriage driving said cutters and said punching and marking devices, and feed mechanism driven by the main shaft driving said cutter-frame and controlled by said 50 control spindle.

2. In an automatic tile-machine, the combination, with the main frame and a main shaft journaled therein, of driving rolls journaled in said frame, a control spindle 55 journaled in said frame geared with said driving rolls, a carriage, carrying guide rolls, movable on said frame, means driven by the control spindle for reciprocating the carriage, the said rolls being designated to 60 carry and be moved by the stream of clay; a figure or curve cutter, a rectilinear cutter, a punching device and a marking device mounted on said carriage for cutting, punching and marking the stream of clay, 65 a reciprocating cutter-frame mounted on the

carriage positively driving said cutters and said punching and marking devices, means comprising a cam-member fast on said main shaft for reciprocating said cutter-frame, 70 means mounted on said frame for coacting with said cam-member and preventing the same rotating, and a member secured to the control spindle for disengaging the latter means from the cam-member.

3. In a tile-machine, the combination, with the main frame and a main shaft journaled therein, of driving rolls journaled in the frame, a control spindle journaled in the frame and geared with said driving rolls, a carriage, carrying guide rolls, movable on said frame, means driven by the control spindle for reciprocating the carriage, the said rolls being designated to carry and be moved by the stream of clay, a plurality of devices mounted on said carriage for 80 treating the stream of clay, a sliding frame mounted on the carriage driving said devices, a cam having two oppositely-arranged shoulders fast on said main shaft, a two-armed lever fulcrumed on the main frame 85 having one arm pivotally connected with said sliding frame and the other arm pivotally connected with said cam, a spring-pressed lever fulcrumed on the main frame adapted to coat alternately with the shoulders of said cam and prevent the main shaft 90 rotating, and an arm fast on said control spindle for removing the latter lever from said cam.

4. In an automatic tile-machine, the combination with a reciprocating carriage having a frame, of a reciprocating cutter-frame arranged transversely of the carriage mounted slidable in said frame, a guide detachably attached to the frame, an axle positively 100 geared with said cutter-frame, and a holder for a cutting wire having one end connected with said axle and the other end guided by said guide; a shaft, journaled in the former frame, arranged parallel with the cutter-frame, arms secured to said shaft, gearing comprising a link pivotally connected with said arms positively connecting said shaft with the cutter-frame, and a vertically-guided bow carrying one or more tools over 105 the carriage attached to said link.

5. In an automatic tile-machine, the combination with a reciprocating carriage having a frame, of a reciprocating cutter-frame, arranged transversely of the carriage mounted slidable in said frame, a guide detachably attached to the frame, an axle positively 120 geared with said cutter-frame, and a holder for a cutting wire having one end connected with said axle and the other end guided by said guide; a shaft, journaled in the former frame, arranged parallel with the cutter-frame, gearing comprising a link positively connecting said shaft with the cutter-frame, and a vertically-guided member carrying 125 130

one or more tools over the carriage attached to said link; a second shaft parallel with the former shaft journaled in the frame, means comprising a clutch connecting said shafts, 5 two arms fast on the second shaft, and a vertically-guided bow carrying a lug-cutter under said one or more former tools pivotally attached to said arms.

In witness whereof I have hereunto signed my name this 20th day of October 1910, in 10 the presence of two subscribing witnesses.

JOH. ROTH.
